US00D752994S

(12) United States Design Patent
Fan

(10) Patent No.: US D752,994 S
(45) Date of Patent: * Apr. 5, 2016

(54) PACKAGING BOX WITH BALL

(71) Applicant: NIKE, Inc., Beaverton, OR (US)
(72) Inventor: Richard S. Fan, Portland, OR (US)
(73) Assignee: NIKE, Inc., Beaverton, OR (US)
() Term: 14 Years
(21) Appl. No.: 29/520,765
(22) Filed: Mar. 17, 2015
(51) LOC (10) Cl. 09-03
(52) U.S. Cl. USPC D9/721

(58) Field of Classification Search

(57) CLAIM

The ornamental design for a packaging box with ball, as shown and described.

DESCRIPTION

FIG. 1 is a front perspective view of a packaging box with ball showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top view thereof;

FIG. 7 is a bottom view thereof; and,

FIG. 8 is a rear perspective view thereof.

The broken lines shown represent unclaimed subject matter and form no part of the claimed design.

1 Claim, 5 Drawing Sheets
